UNITED STATES PATENT OFFICE.

ALBERT WILLIAM SNEDDEN, OF BROOKVILLE, PENNSYLVANIA.

FUSE HOLDER.

Application filed February 15, 1924. Serial No. 693,067.

To all whom it may concern:

Be it known that ALBERT W. SNEDDEN, a citizen of the United States, residing at Brookville, in the county of Jefferson and 5 State of Pennsylvania, has invented certain new and useful Improvements in Fuse Holders, of which the following is a specification.

This invention relates to a new and useful improvement in fuse holders and has 10 for its principal object to provide a simple and efficient device which will hold a fuse in a cap wherein is contained the charge of explosive to ignite the fuse in such a manner as to prevent any possibility of danger in 15 the handling of the same.

Another important object of the invention is to provide a fuse holder of the above mentioned character, which is of such a construction as to enable the several parts comprising the same to be readily assembled or 20 disassembled without employing any tools, thus furthermore insuring safety in the handling of the fuse while preparing the same for use.

A still further object of the invention is 25 to provide a fuse holder wherein means is provided for securely holding the fuse in the cap containing the charge of an explosive and additional means is provided to prevent the fuse and the charge in the cap from 30 becoming damaged by water which would consequently result in the loss of the fuse and also cause unnecessary expenses.

A still further object of the invention is 35 to provide a fuse holder of the above mentioned character, which is simple in construction, inexpensive, strong and durable and further well adapted for the purposes for which it is designed.

Other objects and advantages of this 40 invention will become apparent during the course of the following description.

In the accompanying drawings forming a part of the specification, and in which like 45 numerals designate like parts throughout the same.

Figure 1 is a side elevation of my fuse holder showing the same assembled and in 50 position for use.

Figure 2 is a longitudinal section thereof.

Figure 3 is a detail view of the several 55 parts of my invention, and

Figure 4 is a transverse section taken on lines 4—4 of Figure 2 looking in the direction of the arrows.

In the drawings wherein for the purpose

of illustration is shown the preferred embodiment of my invention, the numeral 1 designates an elongated cap which is formed of any suitable metallic material and has its 60 inner end closed as shown at 2 in the drawings for the purpose of providing a means for holding the charge of explosive which may be of such a character as commonly used and preferably I desire to use fulminate of mercury, and this charge is designated by the numeral 3 in Figure 2 of the drawings. Formed at the open end of the cap 1 is the annular flange 4 the purpose of which will hereinafter be more fully 65 described. The cap is furthermore provided with internal threads as shown at 5 in the drawings adjacent the open end thereof for the purpose of locking the fuse holder hereinafter described within the cap. 70

The fuse holder above referred to comprises the sleeve 6 and which is of a diameter slightly less than the diameter of the cap 1 and this sleeve is provided with an annular flange 7 at its outer end as clearly 75 shown in Figures 2 and 3 of the drawings the flange 7 being of the same diameter as the flange 4 formed on the cap 1. The sleeve 6 is also provided with the external threads 8 which are formed adjacent the 80 annular flange 7 and are adapted to cooperate with the internal threads 5 provided on the cap 1.

To facilitate the easy and ready insertion of the fuse A within the sleeve 6, I provide 85 the outer end of the sleeve with diametrically opposed slits 9 the latter extending longitudinally for a suitable distance from the outer end of the sleeve in the manner as clearly shown in Figure 3 of the drawings. 90 Thus the sleeve will be provided with spring jaws which may be readily placed around the fuse A adjacent the inner end thereof and to further hold the fuse A in proper position within the slotted sleeve I provide the 95 spurs 10, the spurs being formed on the inner wall of the sleeve and arranged adjacent the annular flange thereon whereby the same will bite into the fuse and hold the same against longitudinal movement within 100 the sleeve when the same is in position for use.

In assembling my fuse holder, the fuse A is placed within the sleeve 6 so that the inner end of the fuse will extend for a substantial distance beyond the inner end of the sleeve. The spring jaws of the sleeve 105

formed by providing the slits 9 will then be depressed so that the spurs 10 will bite into the fuse and hold the sleeve in position on the latter, the cap 1 is then filled with the proper amount of fulminate of mercury which forms the charge of explosive and the sleeve 6 is then inserted into the end of the cap so that the threaded portion 8 will engage the internal threads 5 and securely hold the sleeve and fuse carried thereby in the cap.

In order to insure the interior of the cap 1 containing the charge of explosive 3 from becoming damaged or inoperative due to the admission of water accidentally within the cap, I provide the rubber gaskets designated generally by the numeral 11 and which is provided with the collar 12 at its outer end and the tubular portion 13. The tubular portion 13 being adapted to extend around the open end of the cap and the collar 12 being disposed over the annular flange 4 and interposed between the flange 4 and the flange 7 provided on the outer end of the sleeve 6 and securely held therebetween when the sleeve has been inserted into the open end of the cap. This construction and arrangement is clearly illustrated in Figure 2 of the drawings. This gasket 11 will provide a tight and water proof joint between the sleeve and the cap and will prevent any water from seeping therebetween and gaining entrance to the bottom of the cap where it is contained the charge of explosive. It is to be further understood that the sleeve 6 is so secured upon the fuse A so as to have the latter extending inwardly within the cap 1 so that the inner end thereof will be in close proximity to the charge of explosive 3.

As the operation of the charge igniting and fuse igniting is well known in the art it is not thought necessary to further go into detail as to this particular feature. It being sufficient to state that the outer end of the fuse A is connected to the dynamite to be exploded in the well known manner.

It will thus be seen from the foregoing description, that a fuse holder has been provided which is of such a construction as to permit the same to be readily disassembled or assembled in a simple and efficient manner and which will furthermore securely hold the fuse in the proper supported position within the cap containing the charge of explosive and will at all times permit a person to handle the same without any danger of becoming injured.

From the foregoing description of the construction of my improved apparatus, it will be seen that I have provided a simple,

inexpensive and efficient means for carrying out the objects of the invention, and while I have particularly described the elements best adapted to perform the functions set forth, it is obvious that various changes in form, proportion, and in the minor details of construction may be resorted to, without departing from the spirit or sacrificing any of the principles of the invention.

Having thus described my invention, what I claim is:

1. A fuse holder of the class described comprising an elongated cap adapted to hold the charge of explosive in the closed end thereof, a sleeve removably supported in the open end of said cap, a fuse having one end thereof extending through said sleeve and terminating at a point in close proximity to said charge of explosive, and a rubber gasket carried on the cap and having portions thereof interposed between the outer ends of said cap and sleeve.

2. A fuse holder of the class described comprising a fuse supporting sleeve, a charge holding cap supporting said sleeve and the inner end of said fuse, and a rubber gasket carried by said cap and having portions thereof disposed between the outer ends of said cap and sleeve.

3. A fuse holder of the class described comprising an elongated cap adapted to hold a charge of explosive in the closed end thereof, an annular flange formed on the open end of said cap, a flanged sleeve extending into said cap and removably secured therein, a fuse fitting in said sleeve and having its inner end extending in close proximity to said charge, and a flanged rubber gasket carried by the open end of said cap and having its flanged portion interposed between the aforesaid flanges.

4. A fuse holder of the class described comprising an elongated cap adapted to hold a charge of explosive in the closed end thereof, an annular flange formed on the outer end of said cap, said cap being internally threaded adjacent the outer end thereof, a sleeve having an annular flange formed on the outer end thereof, said sleeve being externally threaded adjacent its annular flange for securing the same in the open end of said cap, a fuse carried by said sleeve and having its inner end extending within said cap in close proximity to said charge of explosive, and a rubber gasket carried by said cap and having a collar formed thereon at its outer end, said collar being adapted to be interposed between said annular flanges.

In testimony whereof I affix my signature,

ALBERT WILLIAM SNEDDEN.
